[57] **CLAIM**

The ornamental design for a combined toy sewing machine and case therefor, as shown and described.

DESCRIPTION

FIG. 1 is a front right perspective view of a combined toy sewing machine and case therefor showing my new design with the lid in a raised condition and the sewing machine in a lowered position;

FIG. 2 is another front right perspective view thereof with the sewing machine in a raised position;

FIG. 3 is another front right perspective view thereof shown on an enlarged scale with the lid in a closed position;

FIG. 4 is a left side elevational view thereof; and

FIG. 5 is a rear elevational view thereof.

The side opposite to that shown in FIG. 3 is substantially a mirror image of that shown in FIG. 3.

FIG. 1

FIG. 2

FIG. 3
